UNITED STATES PATENT OFFICE.

PERCIVAL W. JONES, OF WARWICK, RHODE ISLAND, ASSIGNOR TO ROSENHEIM CO. INC., OF PROVIDENCE, RHODE ISLAND, A CORPORATION OF RHODE ISLAND.

CHAIN.

Application filed August 25, 1928. Serial No. 302,093.

This invention relates to a chain for use as a bracelet or strap for holding a watch on the wrist of the wearer; and has for its object to provide an extremely flexible, thin band which will be light in weight and comfortable to the wearer.

A further object of the invention is the provision of a chain which will present a smooth, flat inner or bottom surface for engagement with the arm of the wearer to afford great comfort in being worn and at the same time give a finished ornamental appearance to the rear surface of the chain.

The invention further consists in the provision of a hollow sheet metal filler member carried by each body link between the ends of the arms embracing the connecting links, which locks the arms in position and affords a highly attractive appearance to the back of the bracelet.

With these and other objects in view, the invention consists of certain novel features of construction, as will be more fully described, and particularly pointed out in the appended claims.

In the accompanying drawings:

Fig. 1 is a top plan view of the links of the bracelet in connected series.

Fig. 2 is a bottom view thereof.

Fig. 3 is a perspective view of the body link.

Fig. 4 is a perspective view of the connecting frame link.

Fig. 5 is a perspective view of the filler member.

Fig. 6 is a bottom view showing the relation of the body link and connecting frame link before the arms of the body link are in folded position.

Fig. 7 is a bottom view showing the arms of the body link as folded about portions of the frame connecting link.

Fig. 8 is a bottom view showing the filler member as positioned in the assembly as illustrated in Fig. 7.

Fig. 9 is a bottom view showing the next step in the assembly after Fig. 8, with the side fingers of the body link folded into position.

Fig. 10 is a sectional view on line 10—10 of Fig. 9.

Fig. 11 is a sectional view on line 11—11 of Fig. 9.

In chain structures such as are used as bracelets or used as straps for wrist watches, it is desirable that the same be thin, light

in weight and smooth to the wrist as well as extremely flexible in order that great comfort may be afforded to the wearer of the same, and in order to accomplish these results, I have provided a series of sheet metal body links each having arms to extend thru the frame connecting links, the latter having its end portions offset sufficiently to lie flush on the bottom surface with the folded arms, and I have also provided a filler member positioned in the space between these folded arms and flush therewith on the bottom surface, which is held in place by fingers on the sides of each of the links which are folded in to engage the ends of the filler member and which also lie flush on their bottom surface with the folded arms and the surface presented by the filler member; and the following is a detailed description of the present embodiment of this invention illustrating the preferred means by which these advantageous results may be accomplished:

With reference to the drawings, 12 designates the body link which is made of sheet metal and has a top plate 13 with end arms 15, each of which extends thru the frame-shaped connecting links 16 at each end thereof, to join the adjacent body links together.

The frame link 16 is generally rectangular in shape with a central opening 17 forming side bars 18 which are swaged to be substantially round in construction and in the same swaging operation the ends 20 of this frame link are offset so that when the end arms 15 are wrapped about the cross bars 18 they will lie substantially flush with the offset portions 20 of the frame connecting links, as clearly illustrated in Fig. 11.

By hinging the body links together in this manner an extremely flexible connection is formed and due to the rounding of the cross bars and folding of the end arms thereabout a substantially perfect pivotal or hinge action is provided such that the adjacent links may be swung back to back without danger of breaking the bracelet.

In order to make a smoother back surface for the chain structure, a filler member 21 which is of substantially channel shape in cross section, as illustrated in Figs. 5 and 11, is formed from sheet stock with its bottom wall 22 and opposite substantially parallel walls 23 extending at substantially right angles from the bottom wall 22. The dimension of the parallel walls 23 is such that when

this filler is positioned in a link with its edges in contact with the top plate 13, as illustrated in Fig. 11, its bottom wall 22 will lie flush with the folded arms to make a smooth bottom surface for the bracelet.

Each of the ends of the filler member is formed as illustrated at 24, in Fig. 5, to lie in contact with the bottom surface of the top plate 13 and the side fingers 14 of each of the links are folded inwardly toward each other to overlie these portions 24 and securely hold this member in position.

It will be observed that the extent of the bottom surface of the filler member is of a width substantially that of the width of the frame connector links so that when the side fingers are folded inwardly, as illustrated in Figs. 9 and 10, the bottom surface of the bracelet lies substantially in a single plane throughout its extent for smooth contact with the wrist of the wearer.

The filler member 21 fits snugly between the ends of the arms 15 and prevents their moving upwardly to unlock, and thus in addition to providing a smooth surface of a more ornamental appearance it also serves as a lock to prevent the arms from an opening movement due to longitudinal strains exerted upon the chain or bracelet and is formed of thin sheet stock suitably shaped to present the desired surface of an extremely light construction and yet one strong and durable in operation is provided.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A chain comprising a series of sheet metal body links and frame links connecting the same, each of the adjacent body links having an arm extending thru and folded about a frame link to connect them together, and a member positioned in each body link between the ends of the folded-in arms to fill the space therebetween.

2. A chain comprising a series of sheet metal body links and frame links connecting the same, each of the adjacent body links having an arm extending thru and folded about a frame link to connect them together, a member positioned in each body link between the ends of the folded-in arms to fill the space therebetween, and fingers on the sides of each of said body links folded over the members therein to hold the same in assembled relation.

3. A chain comprising a plurality of body links each having a top plate with end arms and side fingers extending rearwardly there-

from, a frame link thru which arms of adjacent body links extend and are folded thereabout, said finger being folded inwardly from each side and flush on the bottom surface with the folded-in arms, and a filler member in each link between the ends of the arms and flush therewith with its ends extending between said fingers and the top plate whereby the same is held in position.

4. A chain comprising a plurality of substantially rectangular sheet metal body links, each having a top plate with end arms extending rearwardly therefrom, rectangular frame links with an open center and of a width less than the width of the body link, the arms of adjacent body links extending thru the opening of a frame link and folded thereabout to hingedly connect the links together, the side of the frame links being offset to lie flush with the folded arms.

5. A chain comprising a plurality of substantially rectangular sheet metal body links, each having a top plate with end arms extending rearwardly therefrom, rectangular frame links with an open center and of a width less than the width of the body link, the arms of adjacent body links extending thru the opening of a frame link and folded thereabout to hingedly connect the links together, the sides of the frame links being offset to lie flush with the folded arms, a filler member between the arms of each link substantially channel shape in cross section with the edges of its opposite walls substantially in contact with the top plate and of a dimension to space its bottom wall flush with said folded arms.

6. A chain comprising a plurality of substantially rectangular sheet metal body links, each having a top plate with end arms and side fingers extending rearwardly therefrom, rectangular frame links with an open center and of a width less than the width of the body link, the arms of adjacent body links extending thru the opening of a frame link and folded thereabout to hingedly connect the links together, the side of the frame links being offset to lie flush with the folded arms, a filler member between the arms of each link substantially channel shape in cross section with the edges of its opposite walls substantially in contact with the top plate and of a dimension to space its bottom wall flush with said folded arms, and the portions of said member beyond the sides of said frame link extending substantially in contact with said top plate and said side fingers folded over said extensions to hold the members in place, said folded-over fingers lying substantially flush with the folded arms and said filler member.

In testimony whereof I affix my signature.
PERCIVAL W. JONES.
